(57) **CLAIM**

The ornamental design for a beverage container, as shown and described.

DESCRIPTION

FIG. 1 is an isometric view of a first embodiment of a beverage container showing our new design;

FIG. 2 is a left side view of the beverage container of FIG. 1;

FIG. 3 is a right side view of the beverage container of FIG. 1;

FIG. 4 is a rear view of the beverage container of FIG. 1;

FIG. 5 is a front view of the beverage container of FIG. 1;

FIG. 6 is a top view of the beverage container of FIG. 1.

FIG. 7 is a bottom view of the beverage container of FIG. 1.

FIG. 8 is an isometric view of a second embodiment of a beverage container showing our new design;

FIG. 9 is a left side view of the beverage container of FIG. 8;

FIG. 10 is a right side view of the beverage container of FIG. 8;

FIG. 11 is a rear view of the beverage container of FIG. 8;

FIG. 12 is a front view of the beverage container of FIG. 8;

FIG. 13 is a top view of the beverage container of FIG. 8;

and,

FIG. 14 is a bottom view of the beverage container of FIG. 8.

The broken lines in the drawings depict portions of the beverage container that form no part of the claimed design.

1 Claim, 8 Drawing Sheets
